UNITED STATES PATENT OFFICE.

LAWRENCE E. GOELLER, OF CIRCLEVILLE, OHIO.

COMBINATION WHISK-BROOM HOLDER AND SHOE POLISHER.

Application filed June 11, 1925. Serial No. 36,506.

To all whom it may concern:

Be it known that I, LAWRENCE E. GOELLER, citizen of the United States, residing at Circleville, in the county of Pickaway and State of Ohio, have invented certain new and useful Improvements in Combination Whisk-Broom Holders and Shoe Polishers; and I do hereby declare the following to be a full, clear, and exact description of the invention, such as will enable others skilled in the art to which it appertains to make and use the same.

My invention is a combination whisk broom holder and shoe polisher, and its principal object is to provide a toilet article of this character which is compact and can be carried in a pocket-book, handbag or other small receptacle.

Further, the invention contemplates a case for normally receiving and retaining a whisk broom which upon its removal from the case will permit the latter to be employed to shine or wipe shoes.

Still another object of the invention is to provide a toilet article of this character adapted to receive a person's hand when the device is used for shoe shining purposes, and which is provided with a pocket smaller than the cross sectional area of the case to receive the hand of a woman, or when not in use can be utilized to retain a shoe shining cloth or various toilet articles.

Another important object of the invention is to provide a combination whisk broom retaining case and shoe polisher which includes a detachable shoe shining element, which may be removed and thrown away when worn, and a new shoe shining element arranged in its place.

With the preceding and other objects and advantages in mind, the invention consists in the novel combination of elements, arrangement of parts and operations to be hereinafter specifically referred to, claimed and illustrated in the accompanying drawings, wherein,

Figure 1 is a perspective of the device.

Figure 2 is a similar view of the device as used as a shoe polisher.

Figure 3 is a horizontal sectional view, and,

Figure 4 is a vertical sectional view.

Referring to the drawing in detail, wherein similar characters of reference denote similar parts throughout the several views, numeral 5 designates an elongated

strip of flexible material possessing the necessary tenacity such as leather, and has one half its length of a greater width than the other, as indicated at 6. This wider part 60 of the length of material 5 has its opposite longitudinal edges turned at right angles to the length of material 5 to afford end walls 7. Extending transversely of the wider part 6 of the length of material 5 is an elongated strip of flexible material 10, whose opposite ends are turned at right angles as at 11 and disposed upon the inner faces of the end walls 7 and are secured to the latter by sewing or stitching the same as at 12. As illustrated in the drawing, the wider part of the strip 5 and the sheet 10 provide a tapered open ended casing, which conforms to the contour of a whisk broom and normally holds the same as shown in Figure 1. The opposite half of the strip constitutes a flap 5' adapted to be folded upon the casing to hold the whisk broom therein.

A substantially rectangular shoe shining 80 element which may be felt, flannel or other material having a smooth finish as shown in Figure 2, and as designated by the numeral 15. Pairs of resilient male fastening elements are carried by the under face of this shoe shining element, and are disposed at the ends thereof. These resilient fastening elements 16 are adapted to be detachably engaged with resilient sockets for cooperating with female fastenings 17 secured to the outer face of the sheet 10 at the ends thereof.

In using the device as a shoe polisher, the whisk broom is first removed and one hand inserted in the wider end of the casing, defined by the end 6 of the strip 5 and the sheet 10 to dispose the shoe shining element upon the palm of the hand.

In order to accommodate a smaller hand, such as a woman's, a pocket 20 is provided and which consists of a strip of flexible material 21 which extends transversely of the strip 10, and is disposed between this strip and wider end of the strip 5. The opposite ends of this strip 21 are turned inwardly toward the strip 10, and has its marginal edges secured to the latter by sewing or stitching 23. The outer end of this strip 20 is also turned inwardly and secured to the strip 10 as at 24.

When the whisk broom is received in the case, the flap 5' overlies the shoe shining

element, and is detachably connected with the lower end of the strip 10 by means of co-acting fastenings 25, carried by this strip 10 and flap 5', respectively.

5 While I have illustrated and described one embodiment of the invention, I wish to emphasize that I do not limit myself to the exact construction set forth, but that I may make alterations and modifications therein, 10 and such alterations and modifications are only governed by the appended claims.

What I claim is:—

1. A shoe shining device comprising an open ended casing adapted to receive the 15 human hand, a shoe shining element detachably carried by one wall of the casing and extending entirely across the same, and a flap carried by one end of the casing and normally overlying the shoe shining element, 20 and means for detachably connecting the free end of the flap to the casing.

2. A device of the character described comprising an elongated strip of flexible material having approximately half its 25 length wider than the remaining half, the former having its longitudinal edges extended in parallelism to afford end walls, while the latter half of the length constitutes a flap, a flexible wall arranged in opposed relation to the wider half of the strip and being substantially the same length as the former, and having its opposite ends secured to the end walls to afford with the former and the adjacent part of the first mentioned strip an open ended casing for the reception of the 30 human hand, a shoe shining element carried by one wall of the casing, the flap being adapted to normally overlie the shoe shining element, means for detachably connecting the free end of the flap of the casing, and a strip of flexible material arranged transversely within the casing and disposed in spaced relation to one wall thereof and with the latter defining a hand receiving compartment, the hand receiving compartment being of less 35 cross sectional area than the cross sectional area of the casing.

of the human hand, a shoe shining element carried by one wall of the casing, and the flap being adapted to normally overlie the shoe shining element, and means for detachably connecting the free end of the flap to 40 the casing.

3. A device of the character described comprising an elongated strip of flexible material having approximately half its length wider than the remaining half, the former 45 having its longitudinal edges extended in parallelism to afford end walls, while the latter half of the length constitutes a flap, a flexible wall arranged in opposed relation to the wider half of the strip and being substantially the same length as the former, and having its opposite ends secured to the end walls to afford with the former and the adjacent part of the first mentioned strip an open ended casing for the reception of the 50 human hand, a shoe shining element carried by one wall of the casing, the flap being adapted to normally overlie the shoe shining element, means for detachably connecting the free end of the flap of the casing, and a strip of flexible material arranged transversely within the casing and disposed in spaced relation to one wall thereof and with the latter defining a hand receiving compartment, the hand receiving compartment being of less 55 cross sectional area than the cross sectional area of the casing.

In testimony whereof I affix my signature.

LAWRENCE E. GOELLER.
